CLAIM

The ornamental design for a double barrel box, as shown and described.

DESCRIPTION

FIG. 1 is a perspective view of a double barrel box. FIG. 2 is a top view of the double barrel box of FIG. 1. FIG. 3 is a bottom view of the double barrel box of FIG. 1. FIG. 4 is a left view of the double barrel box of FIG. 1. FIG. 5 is a back view of the double barrel box of FIG. 1. FIG. 6 is a front view of the double barrel box of FIG. 1. FIG. 7 is a right view of the double barrel box of FIG. 1. FIG. 8 is a perspective view of an interior of the double barrel box of FIG. 1; and, FIG. 9 is a perspective view of the opposite side of the double barrel box of FIG. 8. The dash-dash broken lines illustrate portions of a double barrel box and form no part of the claimed design.

1 Claim, 6 Drawing Sheets
